(57) **CLAIM**

The ornamental design for a footwear as shown and described.

DESCRIPTION

FIG. 1 is a front, top, and left side perspective view of an embodiment of a footwear according to the new design; FIG. 2 is a front side elevation view thereof; FIG. 3 is a back side elevation view thereof; FIG. 4 is a left side elevation view thereof; FIG. 5 is a right side elevation view thereof; FIG. 6 is a top plan view thereof; and, FIG. 7 is a back, bottom, and right side perspective view thereof.

The bold broken lines represent stitching and are part of the claimed design.

The broken lines in the drawings show portions that form no part of the claimed design.

1 Claim, 7 Drawing Sheets
